UNITED STATES PATENT OFFICE.

JAMES ROBERT BROWNE, OF LONDON, ENGLAND, ASSIGNOR TO RICHARD ROBERT HUNT AND JAMES MARSHALL UPFILL, OF SAME PLACE, AND WALTER JAMES HUNT, OF WELLINGTON, NEW ZEALAND.

BOTTLE OR SIMILAR VESSEL.

SPECIFICATION forming part of Letters Patent No. 473,379, dated April 19, 1892.

Application filed February 2, 1892. Serial No. 420,081. (No model.) Patented in England February 24, 1891, No. 3,380.

To all whom it may concern:

Be it known that I, JAMES ROBERT BROWNE, a subject of the Queen of Great Britain, residing at 60 Haymarket, London, England, have invented new and useful Improvements 5 in Bottles or Similar Vessels, (patented in Great Britain, No. 3,380, February 24, 1891,) of which the following is a specification.

This invention relates to that type of bottles or similar vessels for holding liquids which are provided with valves and valve-protectors located in their necks, so that the contents can be discharged; but the bottle or vessel cannot be refilled through the necks, which contain 15 the valves and valve-protectors.

The object of my invention is to improve the prior construction of bottles or vessels, whereby the valve and valve-protector can be fitted to the bottle prior to filling the latter 20 and in this condition placed on the market, provision being made for filling the bottle at its bottom portion and then sealing the filling-orifice.

To accomplish this object my invention consists in the features of construction and the combination or arrangement of devices hereinafter described and claimed, reference being made to the accompanying drawings, in which—

30 Figure 1 is a vertical sectional view of a bottle constructed in accordance with my invention. Fig. 2 is a detail sectional view of the top portion of the bottle, showing the valve and valve-protector in position for discharging the liquid. Fig. 3 is a detail side elevation of the valve and valve-protector. Fig. 4 is a top plan view of the protector. Fig. 5 is a bottom plan view of the same. Fig. 6 is a bottom plan view of the valve. Fig. 7 is a 35 sectional view of the protector. Fig. 8 is a sectional view of the valve. Fig. 9 is a detail side elevation of the plug for closing the filling-orifice in the bottom of the bottle. Fig. 10 is a top plan view of the same. Fig. 11 is a detail sectional view showing a modification of the invention. Fig. 12 is a similar view showing another modification. Fig. 13 is a similar view of another modification. Fig. 14 is a detail sectional view of the lower 40 portion of the bottle. Fig. 15 is a similar view showing a modified construction of the plug for closing the filling-orifice, and Figs. 16 and 17 are similar views showing other modifications of the plug for closing the filling-orifice. 50

In order to enable those skilled in the art to make and use my invention, I will now describe the same in detail, referring to the drawings, wherein—

The letter A indicates a valve-seat formed 60 by contracting the internal surface of the bottle-neck. C indicates the valve, and B the valve-protector. The valve C is adapted to accurately fit the valve-seat for closing the bottle and is 65 formed at its periphery with notches C', so that when the valve is open or away from its valve-seat the liquid can be discharged from the bottle. The valve-protector B is formed with notches B' in its periphery and is retained in position by an annular contraction B² of the bottle-neck. The bottom wall of the bottle is formed with a hollow projection J, containing a filling-orifice D and adapted to receive a plug E, so that after the bottle is 70 filled through the filling-orifice D the liquid is confined within the bottle by inserting the plug E into the hollow projection J. The plug E is preferably constructed with radial pins F, adapted to fit corresponding recesses in 75 the hollow projection J for locking the plug in position. The bottle is filled by corking its neck in the usual manner and then inverting the bottle and introducing the liquid through the filling-orifice D, after which the 80 plug E, coated with a suitable cement, is inserted into the hollow projection J, where it is firmly and securely held by the setting of the cement in such manner that it is difficult or inconvenient to remove the plug. 85

By the construction described and shown the valve and valve-protector can be inserted into the neck of the bottle and the latter in this condition can be placed on the market, as the filling-orifice and plug at the bottom 90 portion of the bottle provide means for filling the same independent of the bottle-neck. 95

The valve-protector B is designed to be

rigidly secured to the valve C by inserting a projection B³ on the protector into a recess C² in the valve, Figs. 7 and 8. In the modification Fig. 11, however, the protector B is a separate part secured within the neck of the bottle and the valve C is in the form of a bell. In the modification Fig. 12 the protector B is formed with or attached to the valve C and is provided with channels B⁴ for the passage of the liquid when the valve is open or moved from its seat. In the modification Fig. 13 the protector B is formed by inwardly-extending portions of the bottle-neck. In the modification Fig. 14 the plug E is substantially the same as described with reference to Fig. 1, except that the form of the plug is slightly changed. In the modification Fig. 15 the plug is provided with an annular groove containing a ring E' to engage a corresponding recess in the hollow projection J. In the modification Fig. 16 the plug is screw-threaded to engage a corresponding screw-thread in the hollow projection, and in the modification Fig. 17 the hollow projection and filling-orifice are contiguous to the vertical wall of the bottle or vessel instead of being formed integral at the center of the bottom wall, as in other figures.

Having thus described my invention, what I claim is—

- 30 1. A bottle having a valve C and a valve-protector B, located wholly within its neck, a filling-orifice D in its bottom portion for filling the bottle while the neck and protector are in position, and a plug E, sealed in position to close the filling-orifice after the bottle is filled, substantially as described.
- 35 2. A bottle having a valve C and a valve-protector B, located wholly inside its neck, a hollow projection J in its bottom portion, pro-

vided with a filling-orifice D, and a plug E, 40 secured in the hollow projection to close the filling-orifice after the bottle is filled, substantially as described.

3. A bottle having its interior formed integral with a contraction to constitute a valve-seat, a valve seating on the valve-seat, a valve-protector connected to and moving with the valve and located wholly inside the bottle-neck above the valve, a filling-orifice in the bottom portion for filling the bottle, and a 45 plug E, secured in position to close the filling-orifice after the bottle is filled, substantially as described.

4. A bottle having a valve C in its neck, a protector B, located wholly inside the bottle-neck and rigidly connected with the valve to move therewith as it opens and closes, a filling-orifice D in the bottom portion for filling the bottle while the valve and protector are in the bottle-neck, and a plug E, secured in 50 position to close the filling-orifice after the bottle is filled, substantially as described.

5. A bottle having its neck formed with lower and upper contractions A and B², a valve C, seating on the lower contraction, a 55 valve-protector B, located above the valve and retained in the bottle-neck by the upper contraction, a hollow projection J, with a filling-orifice D, and a plug E, secured in the hollow projection to close the filling-orifice after the 60 bottle is filled, substantially as described.

JAMES ROBERT BROWNE.
